United States Patent [19]

Nakamura et al.

[11] Patent Number: Des. 308,361

[45] Date of Patent: ** Jun. 5, 1990

[54] OPTICAL MEMORY DISK DRIVE

[75] Inventors: **Masakazu Nakamura, Hyogo; Yoshihiko Sugiyama, Nara; Susumu Yamamoto, Osaka, all of Japan**

[73] Assignee: **Matsushita Electric Industrial Co., Ltd., Osaka, Japan**

[**] Term: **14 Years**

[21] Appl. No.: **71,223**

[22] Filed: **Jul. 8, 1987**

[30] Foreign Application Priority Data

Mar. 6, 1987 [JP] Japan 62-8621

[52] U.S. Cl. **D14/109**

[57] CLAIM

The ornamental design for an optical memory disk drive, as shown.

DESCRIPTION

FIG. 1 is a front, top and right side perspective view of an optical memory disk drive showing our new design; FIG. 2 is a rear, bottom and left side perspective view thereof; and

FIG. 3 is a left side elevational view thereof on an enlarged scale.

FIG. 1

FIG. 2

FIG. 3
